UNITED STATES PATENT OFFICE.

ELLEF ELLEFSON, OF APPLETON, WISCONSIN.

PULP BREAKER.

Application filed July 24, 1922. Serial No. 576,980.

To all whom it may concern:

Be it known that I, ELLEF ELLEFSON, a citizen of the United States, residing at Appleton, in the county of Outagamie and State 5 of Wisconsin, have invented certain new and useful Improvements in Pulp Breakers, of which the following is a specification.

This invention relates to improvements in machines for preparing fibrous material 10 for the manufacture of paper, and more particularly to machines known in the art as pulp breakers.

One object of the invention is to provide a machine of this character wherein a pulp 15 of fibrous material may be quickly and efficiently separated and otherwise prepared for the screening and other subsequent operations, without tearing or cutting the fibers thereof, or otherwise impairing the quality 20 of the pulp.

Other objects and advantages of the invention will be apparent to those skilled in the art from a reading of the following specification taken in connection with the 25 accompanying drawings, wherein one form of the invention is illustrated.

In the drawings—

Fig. 1 is a top plan view, partly in section, 30 of a machine constructed in accordance with the present invention;

Fig. 2 is a side elevation, partly in section; and

Fig. 3 is an end elevation.

Referring more in detail to the drawings, the machine is shown as comprising a 35 casing 10, provided with twin cylinders 11 and 12, disposed side by side and in parallel relation, and divided centrally of the casing by a longitudinally extending partition 13.

The casing is formed of two complementary 40 sections 10^a and 10^b hinged together along one side of the machine at 10^c, so as to enable the upper section being removed or raised from the lower section at any time 45 in order to clean the interior of the machine or make repairs. When in use, however, it is preferred to secure the two sections together by means of cap screws, or the like, which engage through flanges carried 50 by the sections at their abutting edges. The lower section is provided with a plurality of depending feet or supporting standards 10^d to facilitate in properly mounting the machine.

Each of the cylinders 11 and 12 are divided into a plurality of compartments 11^a

and 12^a respectively by a series of transverse partitions 11^b and 12^b, the partitions and likewise the compartments of one section being staggered with relation to those of the other, as shown more clearly in Fig. 1 of the drawings.

A rotatable shaft 14 extends centrally through each of the cylinders longitudinally thereof. These shafts being journaled at 65 opposite ends in suitable bearings 14^a, supported upon brackets 15 carried by the lower section of the casing. At one end of each of these shafts, a pulley 14^b is mounted, each designed to be connected by a belt or 70 the like, with a suitable source of power. In practice it is proposed to have both of the pulleys 14^b the same size and to drive the same from a single driving pulley, so that the two shafts 14 will be rotated at the 75 same speed, the direction of rotation being also the same and as indicated by the arrows in Fig. 1.

The intervening or dividing longitudinal partition 13 extending between the cylinders 80 11 and 12 is provided with a plurality of ports 16, and these ports are so arranged with respect to the compartments 11^a and 12^a, that the pulp in passing through the machine from the inlet 17 to the outlet 18 85 thereof must travel or flow alternately back and forth from one cylinder to the other until each of the compartments has been traversed. Mounted upon the shafts 14 in each of the cylinders are a plurality of alternate 90 propeller and breaker elements 19 and 20 respectively, the former being in the form of suitably constructed blades 19^a, mounted at an angle of approximately 45° with respect to the longitudinal axis of the shaft, 95 and the latter being in the form of flat blades 20^a. With the exception of the inlet and outlet compartments 12^c and 12^d respectively of the cylinders 12, each of the compartments of each cylinder has mounted 100 therein one propeller member 19 and one breaker member 20, and each of said compartments, with the exceptions just noted, also is provided with two ports in the dividing longitudinal partition 13, which—in 105 view of the staggered relation of the compartments previously described—act one as an inlet and the other as an outlet, as will be readily understood. The inlet and outlet compartments 12^c and 12^d in the particular embodiment of the invention illustrated,

are slightly smaller than the other com-

parts of the machine, and are provided with only one port each, in the partition 13, and a breaker and propeller element, respectively.

5 In the operation of the machine, the pulp, of a consistency of from one-half to one and one-half per cent, or greater, is fed in through the inlet 17 under a slight head. In passing into the machine the pulp first flows into the inlet compartment 12^a thereof, from which, through the head under which the material is fed into the machine and augmented by the action of the breaker element in said compartment, the said pulp or 10 material is fed through the port 16 of the inlet compartment 12^a and into the adjacent compartment of the cylinder 11. In this compartment the pulp is acted upon both by a propeller and a breaker element, and then 15 passes into the next compartment of the cylinder 12, and so on alternately back and forth from one cylinder to the other through all of the remaining compartments in succession, and finally into the outlet compartment 12^a, from whence the pulp flows out to be subjected to the screening and other 20 subsequent operations preparatory to its use in the final manufacturing processes.

30 To better facilitate an accurate understanding of the improvements, arrows have been placed in Fig. 1 to show the travel of the pulp through the machine.

In practice, the present improvements have been found to produce pulp of better 35 quality than has been possible with machines of the various types and constructions heretofore available. Not only is the separation of the fibers more complete but the tearing and cutting of the same are greatly reduced.

40 As will be obvious, the degree of breaking, or, in other words, the condition of the pulp as it leaves the machine may be regulated to a certain extent by the speed with which the propeller and breaking elements are 45 driven and also by the size of the port openings. It will also be obvious that the present improvements are not limited to the particular number of compartments or breaker and propeller elements illustrated in the particular 50 form of the invention herein described, for obviously, without departing from the scope of the present invention, the machine might be constructed with a greater or lesser number of these elements, as well as 55 different arrangements thereof. In other words, the present improvements are susceptible of various changes and modifications, without departing from the spirit or scope thereof and accordingly, it is not desired to limit or restrict the same to the particular construction or arrangement of parts herein illustrated, except as appears in the appended claims.

60 1. In a machine of the class described, a plurality of cylinders arranged side by

side and provided with communicating ports therebetween, an inlet and an outlet, and means for causing the pulp in its passage through said machine to flow back and forth from one of said cylinders to the other 70 through said ports.

2. In a machine of the class described, a plurality of cylinders arranged side by side, and provided with communicating ports therebetween, an inlet and an outlet, means 75 for causing the pulp in its passage through said machine to flow back and forth from one of said cylinders to the other through said ports, and means for operating upon said pulp during such flow to separate the 80 fibers thereof.

3. In a machine of the class described, a plurality of cylinders composed of hinged complementary sections, alternate transverse partitions dividing each cylinder into a plurality of compartments, the compartments of each cylinder communicating with those of the other through intervening ports, an inlet and an outlet, and means for causing the pulp in its passage through the said 90 machine to flow alternately through the compartments of said cylinders.

4. In a machine of the class described, a plurality of cylinders composed of hinged complementary sections, alternate transverse 95 partitions dividing each cylinder into a plurality of compartments, the compartments of each cylinder communicating with those of the other through intervening ports, an inlet and an outlet, means for causing the pulp in its passage through the said machine to flow alternately through the compartments of said cylinders, and means acting to 100 separate the fibers of said pulp during such passage.

5. In a machine of the class described, a casing provided with twin cylinders separated by a longitudinally disposed partition having a series of ports therein, means in each cylinder for breaking up the pulp and separating the fibers thereof, an inlet and an outlet, and means for causing the pulp in its passage through said machine to flow alternately back and forth through said 110 ports from one of said cylinders to the other. 115

6. In a machine of the class described, a casing provided with twin cylinders separated by a longitudinally disposed partition having a series of ports therein, a rotatable shaft in each cylinder having laterally projecting blades thereon, certain of said blades acting to propel the pulp forwardly through said machine, and others of said blades acting as beaters to break up the pulp and separate the fibers thereof, said pulp passing back and forth through said ports during such action.

7. In a machine of the class described, a casing provided with twin cylinders separated by a longitudinally disposed partition 120

having a series of ports therein, a rotatable shaft in each cylinder having laterally projecting blades thereon, certain of said blades acting to propel the pulp forwardly through 5 said machine, and others of said blades acting as beaters to break up the pulp and separate the fibers thereof, and means whereby the pulp in its passage through the machine is forced to travel back and forth 10 through said ports from one cylinder to the other.

8. In a machine of the class described, a casing provided with twin cylinders separated by a longitudinally disposed partition 15 having a series of ports therein, a rotatable shaft in each cylinder having laterally projecting blades thereon, certain of said blades acting to propel the pulp forwardly through said machine, and others of said blades acting 20 as beaters to break up the pulp and separate the fibers thereof, and means whereby the pulp in its passage through the machine is forced to travel back and forth through said ports from one cylinder to the 25 other, said means being in the form of transverse partitions mounted in each of said cylinders.

9. In a machine of the class described, a casing provided with twin cylinders separated by a longitudinally disposed partition 30 having a series of ports therein, transverse partitions in each cylinder arranged in such wise as to provide compartments therein,

the compartments of one cylinder being staggered with relation to those of the other 35 and said ports being so arranged with respect to said compartments that the pulp in passing through the machine must travel alternately back and forth from one cylinder to the other. 40

10. In a machine of the class described, a casing provided with twin cylinders separated by a longitudinally disposed partition 45 having a series of ports therein, transverse partitions providing compartments in each cylinder, said ports being so arranged with respect to said compartments that the pulp in passing through the machine must travel alternately back and forth from one cylinder to the other, and propeller and breaker 50 means in each cylinder.

11. In a machine of the class described, a casing provided with twin cylinders separated by a longitudinally disposed partition 55 having a series of ports therein, transverse partitions providing compartments in each cylinder, said ports being so arranged with respect to said compartments that the pulp in passing through the machine must travel alternately back and forth from one cylinder to the other, and propeller and breaker 60 means in each of said compartments.

In testimony whereof, I have subscribed my name.

ELLEF ELLEFSON.
